UNITED STATES PATENT OFFICE.

HENRY C. FENTRESS, OF ALTON, ILLINOIS.

DEVICE FOR CONVEYING SOUNDS TO MOVING-PICTURE SCREENS.

1,276,198.

Specification of Letters Patent. Patented Aug. 20, 1918.

Application filed May 25, 1916. Serial No. 99,821.

To all whom it may concern:

Be it known that I, HENRY C. FENTRESS, a citizen of the United States, residing at Alton, in the county of Madison, State of Illinois, have invented certain new and useful Improvements in Devices for Conveying Sounds to Moving-Picture Screens; and I do hereby declare the following to be a full, clear, and exact description of the invention, such as will enable others skilled in the art to which it appertains to make and use the same.

This invention relates to a device for conveying sounds to a moving picture screen.

An object of the invention resides in the provision of a device by means of which sounds such as voices or those produced by musical instruments may be carried to moving picture machines so that it will appear to the audience that the sounds are produced by the players who are depicted on the screen.

A further object of the invention resides in the provision of a construction of this character so that the persons producing the sounds may be disposed out of the sight of the audience but so that they can observe the screen.

With these and other objects in view, such as will appear as my description progresses, my invention comprises the combination and arrangement of parts as set forth in and falling within the scope of the appended claim.

In the drawing:

Figure 1 is a sectional view taken through a device constructed in accordance with my invention;

Fig. 2 is a detail of the sound receivers;

Fig. 3 is a plan view, and

Fig. 4 is a detail showing the arrangement behind the screen.

In the drawing, I have illustrated, diagrammatically, a moving picture theater which includes an inclosure 1 in which the moving picture projecting machine 2 is mounted and an assembly room 3 for the audience. The rear portion of this room is covered by a sub-ceiling 4 and the forward portion by a platform 5 which is arranged below the plane of the sub-ceiling. This sub-ceiling 4 and the platform 5 are both arranged below the main ceiling 6 and the edges of the sub-ceiling and platform lie in substantial alinement with each other leav-

ing a space 7 therebetween. The screen 8 is arranged remote from the projecting machine 2 and a space 9 lies between this screen and a wall 10. A plurality of tubes 11 extend from the space 12 between the ceiling 6 and the platform 5 and thence over the sub-ceiling 4. At the front end of this sub-ceiling the tubes turn downwardly and extend between the screen 8 and the wall 10, as at 13. Thus when a sound is produced in the space 12 it will be carried by the tubes and will reach the room 3 by way of the screen.

In order that these sounds may be carried directly to the screen and prevented from entering the room 3 through the space 7, I have provided the ends of certain of the tubes 11 with conical mouth pieces 14 which are formed preferably of rubber and are adapted to fit over the mouths of the persons producing the sounds. Certain other of the pipes are provided with relatively larger sacks 15 which have openings 16 therein for the reception of the mouth of the operator and have side openings 17 through which the operator may pass his hands and arms so that musical instruments may be played within the same. These sacks are made preferably of rubber so that they will fit tightly around the arms of the operator and consequently the sound will all be transmitted through the tubes to the screen. The form of these mouth pieces and sacks may be changed at will and I contemplate also the variation of the size of these members as the necessity arises.

In operation a party of operators will assemble upon the platform 5 and as the pictures are projected upon the screen 8 they will produce sounds directly into the mouth pieces 14 and the sacks 15 so that the sounds will be transmitted to the screen and it will appear to the audience that they are produced by the players depicted on the screen. It is to be noted that the operator will have full view of the screen by way of the space 7 so that their voices will be timed with the action of the players on the screen. In this manner the pictures will appear to talk.

While I have illustrated and described a particular embodiment of my invention, it has merely been for the sake of convenience and I do not wish to be limited to that particular embodiment as it is obvious that numerous changes may be made in the details

of construction without departing from the spirit of the invention or exceeding the scope of the appended claim.

What I claim is:—

5 A structure of the class described including a room having a main ceiling and opposite walls, a screen in spaced relation to one wall, a sub-ceiling in spaced relation to the main ceiling and extending from the wall 10 back of the screen and terminating short of the other wall, a platform in spaced relation to the main ceiling at a lower level than the sub-ceiling and extending from the wall opposite to the screen and terminating below

the free edge of the sub-ceiling, the free 15 edges of the sub-ceiling and platform being spaced apart so as to provide a view between the same from above the platform to the screen, and means supported between the ceiling and sub-ceiling for conducting sound 20 from the space above the platform to the space between the screen and adjacent wall.

In testimony whereof, I affix my signature, in the presence of two witnesses.

HENRY C. FENTRESS.
